UNITED STATES PATENT OFFICE.

THOMAS W. HOLT, OF ELKHART, INDIANA, ASSIGNOR TO CURTAIN SUPPLY COMPANY, OF ELKHART, INDIANA, A CORPORATION OF ILLINOIS.

SASH GUIDE.

Application filed May 25, 1925. Serial No. 32,537.

The present invention relates to sash guides, and has for its object the provision of an improved guide of light, durable and inexpensive construction which is designed to function not only as a guide but also as a weather strip and lock rack.

While the foregoing statement is indicative of the nature of the invention, other objects and advantages will occur to those skilled in the art upon an understanding of the structure of the guide. For the purpose of exemplification, three embodiments of the guide are illustrated in the accompanying drawings and described in the following specification. The invention is susceptible of embodiment in other structurally modified forms, however, coming equally within the comprehensive scope of the claims.

In the drawing—
20 Fig. 1 is a view of a corner of a window sash associated with a guide constructed in accordance with the invention;

Fig. 2 is a front view of one form of the guide;

25 Fig. 3 is a side view of the same;
Fig. 4 is a transverse section taken on the line 4—4 of Fig. 3;

Fig. 5 is a front view of another form of the guide;

30 Fig. 6 is a side view of the same;
Fig. 7 is a transverse section taken on the line 7—7 of Fig. 6;

Fig. 8 is a front view of still another form of the guide;

35 Fig. 9 is a side view of the same; and
Fig. 10 is a transverse section taken on the line 10—10 of Fig. 9.

Reference being first had to that form of the sash guide illustrated in Figs. 1 to 4 inclusive, it will be observed that the guide is attached to a window jamb 10, and is embraced between the side walls 11 of a groove in the outer margin of a sash stile 12. The guide consists essentially of a rigid strip 13 and a resilient strip 14, and may also include a lock rack 15 in the form of a plurality of either integrally associated or separate lock stops 16.

40 The rigid strip 13 is of U-shaped cross section, and is formed of relatively thick sheet metal. The resilient strip 14 is also of U-shaped cross section, but is formed of relatively thin sheet metal. The base 17 of the strip 13 is secured contiguously against the window jamb 10, and the strip 14 is nest-

ed within the strip 13 with the base 18 of the strip 14 against the base 17 of the strip 13. The sides of the strip 14 project from the channel in the strip 13, and are flared laterally at 19 in opposite directions beyond 40 the sides of the strip 13 for resilient engagement with the side walls 11 of the groove in the stile. The flared marginal portions 19 of the strip 14 are of U-shaped cross section to provide relatively broad and frictional bearing beads for sliding coaction with the groove in the stile, but it will be obvious that the marginal portions may be of any other desired cross section. The strip 13 is of less width than the groove in the stile, 45 and is normally maintained in spaced relation to the side walls 11 of the groove by the action of the portions 19 of the strip 14, while the strip 14, when uncompressed by the side walls 11 of the groove, is of greater 50 width across the portions 19 than the groove.

The lock rack 15 is a flat strip which is secured in the channel in the strip 14 against the base 18 of the strip, and is bent outwardly at intervals to provide stops 16 having 55 horizontal upper surfaces 20 and inclined under surfaces 21. The strips 13 and 14 and the lock rack 15 are permanently secured together by a plurality of rivets 22, and the resulting guide structure is secured 60 against the window jamb 10 by a plurality of screws 23.

In Figs. 5 to 7 inclusive is shown another form of the guide, consisting essentially of a rigid strip 24 and a resilient strip 25. The 65 strips 24 and 25 are in a general way similar to the strips 13 and 14 of the form of the guide first described, but the rigid strip, instead of providing a seat for the resilient strip, is nested within such strip, and the 70 sides of the resilient strip are bowed laterally at 26 for engagement with the side walls 11 of the groove in the stile. A plurality of separate lock stops 27 are secured 75 at intervals to the base of the channel in 100 the rigid strip 24 by rivets 28. The stops 27 are formed of sheet metal, and comprise a backing portion 29, two spaced side flanges 30, and a top flange 31 seated upon the upper edges of the side flanges 30.

In Figs. 8 to 10 inclusive is shown still another form of the guide which differs from that just described only in that the position of the rigid strip 24 is reversed in the channel 105 of the resilient strip 25, whereby to present 110

a substantially closed structure. The lock stops 27 are secured within the channel in the rigid strip 24 against the base 32 of such strip, and the base 32 is apertured at 33 above each of the stops to provide openings through which the detent of the sash lock may pass in seating upon the stops. The guide structure is secured to the window jamb 10 by a plurality of relatively long screws 34 which extend from the base 33 of the strip 24 at the front of the guide to the jamb.

In either of the two last described forms of the guide, the contraction of the bowed sides 26 of the resilient strip 25 tends to press the base of such strip more tightly against the jamb 10, and this action of course results in a more weatherproof closure at the jamb.

The sash guide of the invention, is extremely simple in construction, is inexpensive to manufacture, is easy to apply, and is efficient in its operation as a guide, as a weather strip and as a lock rack.

I claim:

1. A sash guide comprising a rigid strip, and a substantially coextensive resilient strip secured to the rigid strip and having a sash-engaging portion projecting laterally beyond such strip for resiliently yielding movement toward the same.

2. A sash guide comprising a rigid strip, and a substantially coextensive resilient strip secured to the rigid strip and having sash-engaging portions projecting laterally in opposite directions beyond such strip for resiliently yielding movement toward the same.

3. A sash guide comprising a rigid strip, and a resilient channel strip secured to the rigid strip and having its sides projecting laterally in opposite directions beyond such strip for resiliently yielding movement toward the same.

4. A sash guide comprising a rigid strip of less width than the groove in the associated sash stile, and a resilient strip of greater width than the groove secured to the rigid strip for resiliently yielding movement toward the same.

5. A sash guide comprising a rigid channel strip of relatively thick sheet metal, and a resilient channel strip of relatively thin sheet metal, said strips being secured one within the other, and the resilient strip having its sides flared laterally in opposite directions

beyond the rigid strip for resiliently yielding movement toward the same.

6. A sash guide comprising a rigid channel strip of relatively thick sheet metal, and a resilient channel strip of relatively thin sheet metal, said strips being arranged one within the other with the bases of the strips contiguously secured together, and the resilient strip having its sides flared laterally in opposite directions beyond the rigid strip for resiliently yielding movement toward the same.

7. A sash guide comprising two strips of channel formation secured one within the other with the sides of one strip projecting laterally in opposite directions beyond the other strip for resiliently yielding movement toward the same.

8. A sash guide comprising two strips of channel formation arranged one within the other with the bases of the strips secured contiguously together and with the sides of one strip projecting laterally in opposite directions beyond the other strip for resiliently yielding movement toward the same.

9. A sash guide comprising two strips of channel formation secured one within the other with the sides of one strip projecting laterally in opposite directions beyond the other strip for resiliently yielding movement toward the same, and a plurality of sash stops secured within the channel against the base of the inner strip.

10. A sash guide comprising a rigid channel strip of relatively thick sheet metal, and a resilient channel strip of relatively thin sheet metal secured about the rigid strip and having its sides flared laterally in opposite directions beyond the rigid strip for resiliently yielding movement toward the same.

11. A sash guide comprising a rigid channel strip of relatively thick sheet metal, and a resilient channel strip of relatively thin sheet metal secured about the rigid strip with the base of one strip adjacent the edges of the sides of the other strip, and having its sides flared laterally in opposite directions beyond the base of the rigid strip for resiliently yielding movement toward the same.

In testimony whereof I have hereunto subscribed my name.

THOMAS W. HOLT.
